MARINE DRIVE LIFT MECHANISM
Joseph E. Urbassik, Saginaw, Mich., assignor to Eaton
Yale & Towne Inc., a corporation of Ohio
Filed June 23, 1965, Ser. No. 466,223
13 Claims. (Cl. 115—41)

ABSTRACT OF THE DISCLOSURE

This invention is a tilting or lift mechanism for an in-board-outboard-type marine drive which provides for shallow water operation and safe beaching of the water craft.

The problem

In any outboard marine drive it is mandatory that provision be made for the propeller housing to freely tilt up in case it should meet an obstruction, such as an underwater stone or the like. This prevents destruction of the propeller.

Further, it is desirable that the propeller can be tilted up for docking, shallow water trolling, and the like. It is further desirable that this type of tilt or lift mechanism be foolproof in operation and economical to manufacture and maintain.

A problem which exists relative to the partial tilting of an outboard propeller is one of excessive thrust load when the propeller is in a partially tilted position. This can impose a destructive force on the tilting mechanism unless appropriate provision is made to safeguard against such emergency conditions.

Further, it is desirable that such a mechanism be not only easy to install, but also easy to disassemble to facilitate periodic service, such as preparation for seasonal use.

When it is considered that provision must be made for steering a boat by changing the angle of approach of the propeller relative to the axis of the boat and for the tilting factors mentioned, it will be evident that substantial problems exist which must be overcome in order to provide a commercially successful marine drive tilting device.

Therefore, a substantial advance to the art would be provided by an improved outboard marine drive tilting mechanism embodying novel features of tilting, with safety features inherent in the tilting, along with simplicity of manufacture for long life durability, dependability and adaptability to different installations.

Objects

Accordingly, it is an important object of this invention to provide a novel outboard marine drive tilt mechanism.

A further object is to provide a novel outboard marine drive tilt mechanism that is operable in any position between two extremes, and under such conditions of operability provides a safety override preventing damage by unexpectedly high propeller thrust.

A further object is to provide a novel, electrically controlled outboard marine tilt mechanism.

Other objects of this invention will appear in the following description and appended claims, reference being had to the accompanying drawings forming a part of this specification wherein like reference characters designate corresponding parts in the several views.

2

FIGURE 1 is a side elevational view, partly in section, of a marine drive tilt mechanism of the present invention, shown in the environment of a boat transom, with the boat in fragmentary outline, and including an inboard marine engine;

FIGURE 2 is a perspective view of the lift cap by which the tilt mechanism of the present invention is connected to the outboard power leg;

FIGURE 3 is a perspective view of the lift cable guide, for passing the cable through the transom of the boat of FIGURE 1;

FIGURE 4 is a front elevational view, partly in section, of the support plate and drive shaft of the present mechanism;

FIGURE 5 is a sectional view taken along the line 5—5 of FIGURE 4; and

FIGURE 6 is an end elevational view taken along the line 6—6 of FIGURE 4.

Before explaining the present invention in detail, it is to be understood that the invention is not limited in its application to the particular construction and arrangement of parts illustrated in the accompanying drawings, since the invention is capable of other embodiments and of being practiced and carried out in various ways. Also, it is to be understood that the phraseology or terminology employed herein is for the purpose of description and not of limitation.

Brief introductory synopsis of the invention

Broadly, the lift-tilt mechanism of the present invention comprises a tension member attached at one end to an outboard gear housing or power leg, and at the other end to a draft or pulling mechanism embodying a suitable mechanical ratio mechanism. In the embodiment of the invention shown, an electrically powered pump supplies pressurized fluid to a hydraulic cylinder which in turn is effective to activate the mechanical ratio device, shown as a pulley and shaft arrangement.

It will become obvious that in extended scope of the invention, other mechanical ratio devices could be used, such as a worm gear operably coupled to the pulley-shaft, for applying a suitable tension to the tension member for appropriate lifting or tilting of the power leg.

A subsidiary aspect of the present invention, in addition to the simplicity of the lifting mechanism, is the use of a safety override device, such as a safety relief valve in the hydraulic pump, to permit bottoming the unit in case of excessive propeller thrust, in order to prevent undue strain from being imposed upon the tensile member, the tilt mechanism, or upon the propeller.

The novel mechanism of the present invention performs two functions:

(1) The propeller can be completely tilted up for beaching or pulling the boat into the dock where the water is extremely shallow. This is the dotted outline position of FIGURE 1; and

(2) The propeller can be tilted to any intermediate position between the solid outline, normal operating position, and the dotted outline position of FIGURE 1. Thus, shallow water trolling is provided by pushing the lift button for a suitably short interval, and the propeller will be tilted up a very small amount. This will reduce the amount of draft as desired for shallow water operation.

The safety relief valve mentioned, is provided with a setting such that it is overcome when the thrust of the

propeller exceeds safe trolling speeds, for example from 1,000 to 1,500 r.p.m. so that the unit will automatically return to the solid outline, tension member slack position, to keep from damaging either the tension member or other parts of the mechanism by the excessive propeller thrust.

As the following more detailed description progresses, these various details of construction and operation will be fully developed.

The environment

FIGURE 1 provides a typical environmental surrounding for the present invention. This includes a boat hull 10, having a rear, transverse transom member 12. Forwardly of the transom 12, or inboard of the hull 10, is a suitable marine engine exemplified by the reference numeral 14.

At the rear of the engine 14 is a flywheel housing 16, to which the operating components of the present invention are mounted.

The transom 12 is provided with a lower main opening 18 through which a drive shaft and universal joint mechanism extend, being enclosed in a housing member 20. An appropriate seal plate 22 is provided around the housing 20 and the transom opening 18.

A mounting plate 21 supports the back part of the engine 14 from the transom 12. The engine 14 is thus at least partially mounted to the transom 12. Also, if desired, mounting blocks may be provided within the boat 10 for additional support. The housing 20 thus extends through the transom hole 18. The seal plate 22 prevents entrance of water into the boat 10.

It is to be noted that a horizontal pivot 24 is provided for the power leg 26, to permit tilting between the solid and dotted outline positions as indicated in FIGURE 1. Also, within the housing 20, there is a vertically disposed pivot mechanism to which a subhousing 28 is supported for turning the power leg back and forth at an angle relative to the axis of the boat 10 for steering the boat in a selected direction. A universal joint mechanism for the drive shaft of the marine engine 14 is contained therefore within the housings 20 and 28. This permits power to be transmitted from the engine 14 to the propeller 30 under any condition of tilt or orientation of the propeller.

A steering mechanism, forming the subject of a co-pending application is also contained within the housings 20 and 28 and this too is of universal joint-type construction to permit steering and tilting of the propeller.

The power leg 26 includes a horizontally disposed shaft at the top, which is connected to the universal joint at the rear end of the drive shaft from the engine 14. Also, the power leg, though not shown, includes a vertically extending shaft, connected by a right angle drive at the top to the horizontal shaft; and this is connected by right angle drive gearing at the bottom to a shaft upon which the propeller 30 is supported. Thus, an operable power train is provided between the engine 14 and the propeller 30 for driving the boat 10 in a selected direction.

A trim pin 32 is provided at the bottom of housing 20 and is engaged by a stop mechanism 34, carried by the power leg 26, for fine adjustment of the normal operating position of the power leg.

The invention

As mentioned before, the operating mechanism of the present invention is attached to and supported by the flywheel housing 16, in turn mounted to the back of the engine 14. Between the operating mechanism and the power leg 26, there is a cable connection 44 to tilt the power leg as desired. The cable 44, as will be brought out hereinafter, extends through the transom 12 of the boat 10 above the housing 20.

At this point, it is believed pertinent to point out, from FIGURE 1, the general orientation of the cable 44 and the manner in which it extends from the power leg 26

The drive end of the power shaft 82

As shown in FIGURES 4 and 6, the right hand end of power shaft 82 has a spacer 84 fitted thereover. Adjacent to the spacer 84, there is applied an annular chain support collar 90. The collar 90 is provided with a transverse hole 94, having one end threaded as indicated. The transverse hole 94 is in axial alignment with a hole 92 at the right end of shaft 82.

A chain connecting pin 96 is threaded at one end and is passed through the chain support collar 90 and shaft 82 and is threaded in as indicated in FIGURES 4 and 6.

The other end of chain connecting pin 96 is formed as a flattened plate 98 having opposed flat surfaces 100. As shown in FIGURE 6, one end of a chain 102 straddles the plate end 98 of connecting pin 96 and a bolt 104 secures these two elements together.

The chain 102 wraps the chain support collar 90 and it will be evident that when an appropriate tensile force is applied against the chain 102, shaft 82 will be rotated. This provides a logical point for discussing the power drive for applying a tensile force to the chain 102, and thus a rotatable force to the power shaft 82.

The power drive

As shown in FIGURES 4 and 6, the power drive mechanism is fastened to the right lower end of the mounting plate 68.

A two-way power cylinder 106 is provided with a bifurcated base 108 that has transverse apertures 110.

A mounting lug 112 extends transversely to mounting plate 68 and is provided with a transverse hole 114, FIGURE 4. A pin 116 is passed through the transverse holes 110 of bifurcated base 108 and the hole 114 of mounting lug 112 to pivotally mount the lower end of the cylinder 106 to mounting plate 68.

Within the cylinder 106 is a piston 118 that is connected to a piston rod 120 which extends out through a suitable packing in the upper end of cylinder 106. The free end of piston rod 120 is formed as a plate 122 having opposed flat surfaces 124.

As shown in FIGURE 6, the other end of chain 102 straddles the plate end 122 of piston rod 120, and the two units are secured together by a bolt 104.

From the foregoing it will be evident that when appropriate power is applied to the power cylinder 106, the piston rod 120 will be correspondingly driven either out or back into the two-way power cylinder 106 to tension or relax the chain 102 and thereby transmit a rotatable force to the power shaft 82.

The hydraulic pump

Although the pump, designated 126 in FIGURE 6, can be put at any suitable location, it is preferably put in close proximity to the power cylinder 106. This simplifies the length of lines, generally simplifies the unit, and makes it more compact. As shown in FIGURE 6, the pump 126 is mounted on the opposite side of mounting plate 68 to the power cylinder 106. The pump 126 includes a base member 128 that has a transversely extending pedestal 130, including a vertically disposed attachment leg 132. Bolts 134 are passed through suitable apertures in the attachment leg 132 and through the lower portion of the mounting plate 68 to support the hydraulic pump 126 in operable position.

The pump 126 includes an electric motor 136 in the upper portion, to which electrical wires are connected as indicated in FIGURE 1.

At the bottom there are two fittings 138 and 140 that are suitably connected to the interior of the pump housing and to which lines 142 and 144 are respectively coupled. Lines 142 and 144 are not designated intake and exhaust from the pump, because it is a reversible unit and thus, depending upon the direction of rotation, one or the other of lines 142 and 144 will be an intake and ex-

haust. Line 142 is suitably connected into the bottom of the power cylinder 106 beneath the piston 118 and line 144 is suitably connected into the top above piston 118 as shown in FIGURE 6.

5 The wiring for the motor 136 of pump 126 is indicated in FIGURE 1. Thus, a two-way switch 146 is mounted at a suitable location in the boat for access by the operator. Lead lines 148 and 150 are connected to a suitable source of power, such as a 12 volt battery or other as used in the boat. The two-way wiring comprises three leads 152, 154 and 156, which as indicated in FIGURE 1, are connected to the motor 136 in the upper part of the pump mechanism 126.

10 As indicated in FIGURE 1, pressing the upper part 158 of the control button of the two-way switch 146 will cause pump rotation in a manner to tilt the power leg 26 upwardly. Pressing the down portion 160 of the button of the two-way switch 146 will cause a reverse operation of the motor and cause the power leg 26 to be lowered to the dotted outlined position, or a small amount as desired:

Cable pulley 48

15 Before describing the operation of the invention, in view of the foregoing control and power features, the cable pulley 48 and its connection to the forward end of cable 44 will now be described in detail.

20 As shown in FIGURE 5, the cable pulley 48 is open on one side to permit anchoring the back end of the cable 44. A boss 162 is provided where the V-groove 164 terminates as shown at the left side of FIGURE 5. The end of the cable 44 is passed over the boss 162 and secured by a clamp 166 that is fastened by bolts 168 to the web 170 of cable pulley 48. An additional bolt and washer 172 holds the very end of the cable 44 down against the inside of the peripheral wall 174 of the pulley 48. This provides extra cable for adjustment. Note that the pulley 48 is flat as along the chord of a circle at 47.

Operation

25 Relative to the operation of the present invention, the following are pertinent:

30 (1) *Raising*.—To raise the marine drive, that is the power leg 26 of FIGURE 1, the upside portion 158 of the switch 146 is pressed. The power leg 26 will tilt from the normal solid line operating position to a lifted position (dotted line) or to any intermediate position selected. When the switch 146 is released, the power leg 26 is stopped in the desired position.

35 (2) *Lowering*.—To lower the power leg 26, the down side 160 of the two-way switch 146 is pressed. The power leg 26 will tilt down from a lifted position to a normal operating position, the solid outline position, or to any intermediate position selected. When the switch 146 is released, the power leg 26 is stopped in the desired position.

40 For performing the foregoing lifting, and lowering, reference is now made to FIGURE 6 for an indication of the hydraulic fluid flow.

Up movement

45 For a lift operation, the up portion 158 of two-way switch 146 is pressed. This causes the motor 136 of the pump 126 to turn in a direction to force compressed fluid from the fitting 140 through line 144 and into the top of the power cylinder 106. Fluid below the piston 118 is exhausted back to the pump 126 through line 142 and fitting 138.

50 This action is effective to press the piston 118 downwardly.

55 Downward movement of piston 118 causes the piston rod 120 to move down, or be retracted into the power cylinder 106, and as shown in FIGURE 6, is effective to tension the chain 102 to rotate the power shaft 82 in a counterclockwise direction.

Looking at FIGURE 5, a clockwise direction 176 is imparted to the cable pulley 48.

Referring now to FIGURE 1, clockwise direction 176 of cable pulley 48 is effective to shorten the cable 44 and cause a lifting or tilting action of the power leg 26.

Down movement

Pushing the down portion 160 of the button of the two-way switch 146 causes the opposite rotation of the motor 136 of the pump 126. This forces fluid out through the fitting 138 and through the line 142 up beneath the piston 118 of the two-way power cylinder 106. Fluid above the piston 118 passes back through line 144 and into the pump 126. This causes the piston rod 120 to be extended from the power cylinder 106 and slacks chain 102 and lets the weight of the power leg 26 of FIGURE 1 rotate the power shaft 82 in a clockwise direction, as shown in FIGURE 6. The clockwise direction on the FIGURE 6 end is counterclockwise direction 178 on the FIGURE 5 end of the mechanism.

As shown in FIGURE 1, this will permit the cable 44 to be paid out and the power leg 26 will move downwardly toward or to the solid outline position of FIGURE 1.

Safety feature

The reason the present mechanism is operable not only at the extremes as represented by the solid and dotted outline positions of FIGURE 1, but also at any intermediate position therebetween is twofold:

(1) The intermediate positions permit shallow water low speed trolling; and

(2) The completely raised dotted outline position permits beaching of the boat without damage to the propeller 30.

Relative to the intermediate, shallow water trolling positions, a safety feature is provided. Thus, the piston 118 of the two-way power cylinder 106 is equipped with a relief valve (shown at 107) which will allow the power leg 26 to return from a fully or any intermediate tilted position to normal operating position should the propeller thrust exceed the design setting. As mentioned above, a typical design setting is in the range from about 1,000 to about 1,500 r.p.m. of the propeller 30 to permit slow speed shallow water trolling.

Should the throttle be accidentally moved to a setting exceeding this r.p.m. or should any other malfunction causing such occur, the thrust of the propeller will overcome the setting of the safety relief valve and the power leg will move automatically to the solid outline position of FIGURE 1, placing all of the thrust against the trim pin 32.

In the normal operating position of the power leg 26, as shown by the solid outline of FIGURE 1, the cable 44 is slightly slack; that is, when the drive is trimmed to maximum forward position and the piston rod 120 of power cylinder 106 is extended. This prevents any excessive strain from being applied against the cable 44 or against the power lift mechanism under any circumstances and thus prevents damage to the unit, the cable, or to the power leg 26.

Extended scope of invention

The present invention has illustrated a two-way powered cylinder 106 as the prime mover for the raising and lowering of the power leg 26. It will be evident that the extended scope of invention would encompass other power mechanisms, either with or without a safety override feature as has been set forth herein in the form of a safety relief valve contained within the mechanism of the piston 118 of the power cylinder 106.

Cable as used herein is to be construed as a tensile member.

The lift device of the present invention can well be designed into a power trim mechanism. This certainly

70 will be desirable under certain conditions to give the boat operator limited control of the drive unit's trim angle.

I claim:

1. In a lift mechanism for the power leg of a marine drive, wherein the drive is powered by an inboard engine and the power leg is located outboard of the transom and is mounted for pivotal movement about a horizontal axis, the power leg being disposed substantially vertically with respect to the transom and is adapted to tilt-up about said horizontal axis upon striking an obstruction while maintaining a continuous drive relation with the inboard engine
  - 15 a support mounted in space in operable relation to said power leg,
  - 16 a rotatable shaft carried by said support,
  - 17 means for rotating said shaft,
  - 18 a tensile element,
  - 19 means connecting one end of said tensile element to said rotatable shaft,
  - 20 and means connecting the other end of said tensile element to said power leg,
  - 21 whereby rotation of said shaft in one direction is effective to shorten said tensile element and tilt said power leg toward a horizontal position; and rotation of said shaft in the opposite direction is effective to lengthen said tensile element and lower said power leg by gravity toward a vertical position, and means in driving relation with said rotatable shaft responsive to the output of the lower leg to control rotation of said shaft.
2. The invention of claim 1 wherein said tensile element is a flexible tensile element.
3. The invention of claim 1 wherein said tensile element is a cable.
- 35 4. In a tilting mechanism for a marine drive comprising a power leg that is movable about a horizontal axis, and having a propeller and a top,
  - 36 a support plate mounted in space in operable relationship to said power leg,
  - 37 a housing at the top of said support plate,
  - 38 a rotatable power shaft journaled within said housing,
  - 39 a cable pulley fixed to one end of said rotatable power shaft,
  - 40 a flexible cable,
  - 41 means anchoring one end of said flexible cable to said cable pulley,
  - 42 means connecting the other end of said flexible cable to said top of said power leg,
  - 43 an annular collar fixed to the other end of said power shaft,
  - 44 a pin passed through said power shaft and through said annular collar and having an exposed end extending beyond the periphery of said annular collar,
  - 45 a chain having one end connected to said exposed pin end and lapping said annular collar,
  - 46 reciprocable, linearly movable power means operably connected to the other end of said chain,
  - 47 and means for powering said power means.
5. In a tilt mechanism for a marine drive comprising
  - 50 a power leg having a propeller, and the power leg being movable about a horizontal axis, and said power leg having a top,
  - 51 a support mounted in space in operable relationship to said top of said power leg,
  - 52 a tubular power shaft housing carried by said support,
  - 53 a rotatable power shaft journaled within said tubular power shaft housing,
  - 54 a cable pulley fixed to one end of said rotatable power shaft,
  - 55 a flexible cable,
  - 56 means anchoring one end of said flexible cable to said cable pulley to wrap thereon,
  - 57 means anchoring the other end of said flexible cable to said top of said power leg,
  - 58 and power means operably connected to said power

- shaft for rotating said shaft in first one direction and then the other, said power means being responsive to the output of the propeller of the power leg to control rotation of said power shaft.
6. The invention of claim 5 wherein said cable pulley comprises a disc-like web having a tubular hub extending transversely thereof to fit over said rotatable power shaft,
- an annular cable groove formed integrally with said web,
- and said groove being open along a chord of a circle generated from said hub as a center and terminating in a rounded boss,
- and means anchoring said cable one end to said web, between said tubular hub and said cable groove, and the cable passing over said base into said groove.
7. In a tilt mechanism for a marine drive comprising a power leg having a propeller, the power leg being movable about a horizontal axis, and said marine drive having a top,
- a support positioned in operable relationship to said top of said power leg,
- a housing carried by said support,
- a rotatable power shaft journaled within said housing, a cable pulley fixed to one end of said rotatable power shaft and having a grooved periphery,
- a flexible cable,
- means anchoring one end of said flexible cable to said cable pulley to ride in said groove,
- means anchoring the other end of said flexible cable to said top of said power leg,
- an annular collar fixed to the other end of said power shaft,
- a pin passed through said power shaft and said annular collar and having an exposed end extending beyond the periphery of said annular collar,
- a chain having one end connected to said exposed pin end and lapping said annular collar,
- a two-way power cylinder pivotally connected at one end to said support, in alignment with said chain and annular collar,
- said power cylinder having a reciprocable piston rod, means connecting the free end of said piston rod to the other end of said chain,
- a two-way pump for hydraulic fluid mounted on said support and operably connected to said two-way cylinder,
- and power means for operating said two-way pump to drive said piston rod of said power cylinder in first one direction and then the other.
8. The invention of claim 7 wherein said power leg is engageable with a fixed stop to absorb the full thrust of said propeller,
- and wherein said two-way pump includes a safety relief valve,
- whereby excessive thrust of said propeller with said power leg in a partially tilted position will overcome the lift potential of said two-way pump and bottom said power leg against said fixed stop to prevent undue strain on said tilt mechanism.
9. In a marine drive for a boat having a transom, an inboard engine mounted in said boat, and having a flywheel housing and an output shaft extending from said flywheel housing through said transom to an outboard power leg,
- an outboard power leg operably connected to said output shaft of said engine and including a propeller that is movable below the water line,
- said power leg being mounted for pivotal movement about a horizontal axis, and having a top cap, a support plate mounted on said flywheel housing, inboard of said boat,
- a housing carried by said support plate and extended transversely to the axis of said boat,
- a rotatable shaft journaled within said housing,

- a cable pulley fixed to one end of said rotatable shaft, a flexible cable,
- means anchoring one end of said flexible cable to said cable pulley for wrap thereon,
- means anchoring the other end of said cable to said top cap of said power leg,
- and power means operably connected to said rotatable shaft to rotate said shaft in first one direction and then the other, said power means being responsive to the output of the propeller of the power leg to control rotation of said rotatable shaft.
10. The invention of claim 9 including a cable passage through said transom,
- a cable guide fastened to said transom in alignment with said cable passage,
- and waterproof seal means around said cable guide and between said cable guide and said cable passage in said transom, permitting said cable to move axially through said transom in a waterproof manner.
11. In a marine drive for a boat having a transom, an inboard engine mounted to said boat and having a flywheel housing and a power shaft extending from said flywheel housing through said transom to an outboard power leg,
- an outboard power leg operably connected to said power shaft, and including a propeller that is movable below the water line,
- said power leg being mounted for pivotal movement about a horizontal axis, and having a top cap,
- a support plate mounted on said flywheel housing, inboard of said boat,
- a tubular housing carried by said support plate, and extending transversely to the axis of said boat,
- a rotatable shaft journaled within said tubular housing, a cable pulley fixed to one end of said rotatable shaft, a flexible cable,
- means anchoring one end of said flexible cable to said cable pulley for wrap thereover,
- means anchoring the other end of said cable to said top cap of said power leg,
- a cable passage through said transom, through which said cable is passed,
- a cable guide fastened to said transom in alignment with said cable passage,
- waterproof seal means around said cable guide and between said cable guide and said cable passage in said transom,
- an annular collar fixed to the other end of said power shaft,
- a pin passed through said power shaft and said annular collar and having an exposed end extended beyond the periphery of said annular collar,
- a chain having one end connected to said exposed pin end and lapping said annular collar,
- a two-way power cylinder pivotally connected at one end to said support, in alignment with said chain and annular collar,
- said power cylinder having a reciprocable piston rod, means connecting the free end of said piston rod to the other end of said chain,
- a two-way pump for hydraulic fluid mounted on said support and operably connected to said two-way power cylinder,
- and power means for operating said two-way pump to drive said power cylinder in one direction and then the other.
12. The invention of claim 11 wherein said power leg is engageable with a fixed stop to absorb the full thrust of said propeller,
- and wherein said two-way pump includes a safety relief valve,
- whereby excess thrust of said propeller with said power leg in a partially tilted condition, will overcome the lifting potential of said pump and bottom said power leg against said fixed stop to prevent undue strain

on said cable, said cable pulley, said power shaft, said chain and said two-way power cylinder.

13. In an inboard-outboard marine drive having an engine disposed inboard of a boat hull and an outboard power leg in continuous drive relation with the inboard engine, said power leg being mounted on the boat hull on a horizontal pivot axis permitting said power leg to tilt-up upon striking an obstruction, power operated means associated with said power leg for tilting said power leg upwardly away from the boat transom to selected positions between a normal power leg operating position and a maximum tilt-up position, said power operated means including means responsive to the output of said power leg to control operation of said power operated means.
